UNITED STATES PATENT OFFICE

165,616

ANIMAL TOY FIGURE

Gertrude Van Tuyl, San Antonio, Tex.

Application June 21, 1951, Serial No. 15,617

Term of patent 14 years

(Cl. D34—2)

To all whom it may concern:

Be it known that I, Gertrude Van Tuyl, a citizen of the United States, residing in San Antonio, county of Bexar, and State of Texas, have invented a new, original, and ornamental Design for an Animal Toy Figure, of which the following is a specification, reference being had to the accompanying drawing, forming part thereof.

I claim:

The ornamental design for an animal toy figure, as shown.

GERTRUDE VAN TUYL.
